UNITED STATES PATENT OFFICE

170,638

FUR SEWING MACHINE

Clare E. Hodgman, Mamaroneck, N. Y., assignor
to Bonis Bros. Fur Machinery Corp., New York,
N. Y., a corporation of New York

Application April 29, 1953, Serial No. 24,751

Term of patent 14 years

(Cl. D70—1)

To all whom it may concern:

Be it known that I, Clare E. Hodgman, a citizen of the United States of America, residing in the city of Mamaroneck, county of Westchester, State of New York, have invented a new, original, and ornamental Design for a Fur Sewing Machine, of which the following is a specification, reference being had to the accompanying drawing forming a part thereof:

Figure 1 is a front view in perspective of a fur sewing machine showing my new design.

Figure 2 is a side view thereof taken from the right side of Figure 1.

Figure 3 is a side view in elevation thereof taken from the left side of Figure 1.

Figure 4 is a front view in elevation thereof.
Figure 5 is a rear view in elevation thereof.
Figure 6 is a top plan view thereof.

I claim:

The ornamental design for a fur sewing machine, as shown.

CLARE E. HODGMAN.
